[57] CLAIM

The ornamental design for a musical instrument digital interface controller, as shown and described.

DESCRIPTION

FIG. 1 is a top plan view of a musical instrument digital interface controller showing our new design;
FIG. 2 is a front elevational view thereof;
FIG. 3 is a left side elevational view thereof;
FIG. 4 is a right side elevational view thereof;
FIG. 5 is a rear elevational view thereof;
FIG. 6 is a bottom plan view thereof; and
FIG. 7 is a perspective view thereof.

FIG.1

FIG.2

FIG.3

FIG.4

FIG.5
